Walter Meyner, Inventor

UNITED STATES PATENT OFFICE.

WALTER MEYNER, OF NEW YORK, N. Y.

SELF-ILLUMINATING NOTEBOOK.

1,313,551.

Specification of Letters Patent.

Patented Aug. 19, 1919.

Application filed September 12, 1918. Serial No. 253,789.

To all whom it may concern:

Be it known that I, WALTER MEYNER, a citizen of the United States, residing at New York, New York, have invented a new and useful Improvement in Self-Illuminating Notebooks, of which the following is a specification.

The objects of my present invention have been to provide a simple, practical and compact form of self-illuminating note book.

Generally speaking the invention resides in the combination with a light-pervious sheet of writing material, of a backing or support for the same, having luminous properties, the combination thus providing in effect an illuminated writing surface. A light-impermeable cover is preferably provided for shielding the illuminated surface, when necessary. The writing material is preferably provided in the form of a pad releasably secured at the back of the support and having a portion stretched across the luminous face of the support.

Other features of the invention will appear as the specification proceeds.

The accompanying drawings illustrate practical embodiments of the invention but these may be changed in various ways to meet different requirements, without departing from the true scope of the invention, as covered in the appended claims.

Figure 1 is a perspective view of one form of the note book, opened up to show its construction.

Fig. 2 is an enlarged and broken detail view of the luminous backing, pad and take-up reel.

Fig. 3 is a perspective view of the book as it normally appears on being opened for writing therein.

Fig. 4 is a broken perspective view of a modified form of the construction.

Fig. 5 is a cross sectional view thereof taken substantially on the plane of line 5-5 of Fig. 4.

7, designates the luminous backing or support, formed of sheet metal or other material suitable for writing and provided in this instance with a readily renewable luminous face in the shape of a sheet 8, of luminous material detachably held to the support by the overstanding clips or fingers 9. The luminous facing may simply be a thin sheet of suitable material impregnated or otherwise treated with a satisfactory luminous paint. The provision of the luminous

facing in this form makes it possible to easily renew the facing whenever necessary.

10, designates the writing material, which 60 may be a semi-transparent or translucent paper, and which is pervious to the light emitted by the backing. This writing material is shown folded in zigzag fashion into a pad 11, disposed flat against the back of 65 the support and bearing at one end against an angularly outstanding lug or stop shoulder 12 on the back of and near one end of the support, the outermost or leading end portion of the strip being doubled or folded 70 back over this stop shoulder and stretched across the luminous face of the support.

This provides an active stretch of writing material which is illuminated, sufficiently for writing purposes, from the luminous 75 backing which supports it, and a supply pad from which additional writing material may be withdrawn as required.

As the strip is used and withdrawn, it may be detached in sections, in the form of 80 separate notes, or the strip may be preserved intact, as by winding it on a reel, such a reel being shown in Figs. 1-3, in the form of a flat plate 13, provided with a clip 14 for the leading edge of the strip and 85 pivoted intermediate its ends, at 15, to a frame 16, which in turn, is pivoted at 17, to the backing at the end opposite the end where the stop shoulder is located. This flat reel structure, when not in use, folds 90 down flat against the support, as shown in Fig. 3, but can be readily extended as shown in Fig. 1, for the purpose of advancing and reeling up the strip.

The pad is shown detachably secured in 95 place at the back of the support, by an overlying back plate or cover 18, which, in the first form illustrated, is hingedly connected to the support at 19 so that it can be readily swung open and in the second form is shown 100 detachably held to the support beneath the clips 20. In the first structure the hinged back is shown provided with an angular lip or flange 21, which springs over the edge of the support to secure this back cover 105 closed (Fig. 3).

By using light paper, pads of compact size but relatively great writing capacity may be made up in this flat thin form. They are readily inserted in place by simply opening up the back, placing them against the stop shoulder and leading the outer stretch 110

across the face of the luminous support. The stop shoulder, with the confining back, hold the pad in shape and cause the strip to draw out evenly, one layer at a time. The 5 stop shoulder need not extend the full depth of the pad as it need only be of such extent as to stop endwise movement of the pack and should not be so high as to prevent easy 10 passage of the paper.

10 To minimize friction against the back of the pack or pad, the back cover may be provided with longitudinal ridges 22, bearing on the pad only along certain lines. This serves also to prevent sidewise travel or 15 slippage of the strip or pad.

As in many cases it is desirable to shield the light emanating from the pad, I propose also to provide a front cover, such as indicated at 23, and which conveniently may be 20 hingedly connected to the support, as indicated. This cover may be used to entirely conceal the light, and may also, when partly opened, be used as a shade for the light. On the inside of this front cover I have shown 25 provided a pocket or compartment 24, which may be utilized as a carrier for detached notes or as a holder for extra pads or luminous facings.

What I claim is:

30 1. In combination with a support, an angularly outstanding stop shoulder at the back of said support substantially at one end thereof, a continuous strip of writing material folded in zigzag outline into a compact pad at the back of the support and resting at one end against the stop shoulder, the outer end of said strip being withdrawn from the pad and folded around the stop shoulder across the face of the support, to enable withdrawal of the strip across the face, as required, a back plate having ridges bearing on the pad and means for releasably 40 securing said back plate to the support.

Copies of this patent may be obtained for five cents each, by addressing the "Commissioner of Patents, Washington, D. C."

2. In combination with a support, having an angularly outstanding stop shoulder at 45 the back substantially at one end thereof, a continuous strip of writing material folded in zigzag outline into a compact pad at the back of the support and resting at one end against the stop shoulder, the outer end of said strip being withdrawn from the pad and folded around the stop shoulder across the face of the support, to enable withdrawal of the strip across said face, as required, and a take-up device for the strip 50 at the end of the support opposite that end where the stop shoulder is located.

3. In combination with a writing support, an angularly outstanding stop shoulder on the back of said support at one end thereof, 60 a strip of writing material folded in zigzag outline into a compact pad at the back of the support, said pad resting at one end against said stop shoulder and having its outer end withdrawn from the body of the 65 pad, folded around over the edge of said shoulder as a guide and passed across the face of the support, means for confining the feed end of the pad to the face of the writing support and means for confining the 70 body of the pad to the back of the support.

4. In combination a writing support for a strip of writing material adapted to be folded over one end and across the face of the support and a flat reel for the used portion of the strip pivoted on the support and foldable flat down upon the support.

In testimony whereof I, WALTER MEYNER have signed my name to this specification in the presence of two subscribing witnesses, 80 this tenth day of September, 1918.

WALTER MEYNER.
